UNITED STATES PATENT OFFICE.

GERMAIN PORET, OF CALAIS, FRANCE.

DESIGN FOR LACE FABRIC.

SPECIFICATION forming part of Design No. 24,293, dated May 7, 1895.

Application filed March 27, 1895. Serial No. 543,407. Term of patent 3½ years.

To all whom it may concern:

Be it known that I, GERMAIN PORET, a citizen of France, and a resident of Calais, France, have invented and produced a new 5 and original Design for Lace Fabric, of which the following is a specification, reference being had to the accompanying drawing, showing a part thereof.

The leading feature of my design consists 10 of a lace fabric having floral ornamentalations that form the common centers for a stem and three volutes provided with leaved branches. At the edge of the fabric is arranged a row of 15 plume-shaped ornaments, while numerous spots are scattered upon its body.

a, is a floral ornamentation that forms the common center for a stem *p*, and three volutes *c*, *d* and *b*, such stem and volutes being

provided with leaved branches *f*, *g* and *h*. At the edge of the fabric is arranged a row of 20 plume-shaped ornaments *i*, while upon the body of the fabric, are scattered numerous spots *j*.

What I claim is—

The design for a lace fabric, substantially 25 as shown.

In testimony that I claim the foregoing as my invention I have signed my name, in presence of two witnesses, this 31st day of January, 1895.

GERMAIN PORET.
